UNITED STATES PATENT OFFICE.

GEORGE W. PAUL, OF PITTSBURG, PENNSYLVANIA.

PARER AND SLICER.

SPECIFICATION forming part of Letters Patent No. 707,798, dated August 26, 1902.

Application filed March 16, 1901. Serial No. 51,510. (No model.)

To all whom it may concern:

Be it known that I, GEORGE W. PAUL, a citizen of the United States of America, residing at Pittsburg, in the county of Allegheny and 5 State of Pennsylvania, have invented certain new and useful Improvements in Parers and Slicers, of which the following is a specification, reference being had therein to the accompanying drawings.

10 This invention relates to certain new and useful improvements in tools or implements for paring and slicing vegetables, and has for its object to provide an implement of this character that will be extremely simple in 15 construction, strong, durable, and comparatively inexpensive to manufacture.

Briefly described, the invention comprises 20 a wire handle shaped to conveniently fit the user's hand, the handle being made of a single piece of wire doubled upon itself, the two parallel arms of the wire beyond the handle forming a frame to hold the parer and slicer. This parer and slicer is made of one piece of material clenched over upon the arms of the 25 frame.

The construction will be hereinafter more 30 specifically described in detail and then particularly pointed out in the claim, and in describing the invention in detail reference is had to the accompanying drawings, forming a part of this specification, and wherein like numerals of reference will be employed for designating like parts throughout the several views, in which—

35 Figure 1 is a front elevation of my improved parer and slicer. Fig. 2 is a transverse vertical sectional view taken on the line 2 of Fig. 1. Fig. 3 is a top plan or end view.

To put my invention into practice, I form 40 from a suitable piece of wire a handle 1. This handle is formed by doubling the piece of wire, indenting or forcing the two strands formed by the doubling inwardly, then outwardly, and then continuing the two arms 45 outwardly in parallel relation, so as to form a frame 2, the wire being doubled so that the two ends thereof will be even. This frame, comprising the two parallel arms, has the parer and slicer mounted thereon, and 50 this parer and slicer is made of one piece of suitable sheet metal 3, substantially rectangular in form, with the two side edges thereof

turned inwardly and clamped upon the arms of the frame, as at 4. Along one edge the metal plate carries an integral extension 5, 55 which is curved upwardly and slightly inwardly at its outer end and forms the slicer. This extension or slicer is provided with a knife-edge 6. At its upper or outer end the plate 3 is bent upwardly at an angle of about 60 forty-five degrees to the body of the plate, and the plate is provided at the base of this inclined portion 7 with a slot 8, the lower edge of the inclined portion being bent back and sharpened to a knife-edge 9. For the 65 purpose of scraping the bottoms of pans, pots, and the like the upper end of the inclined portion 7 is formed with a straight edge, which permits of the same easily entering and cleaning the corners. The plate 3 is preferably provided with the turned-in flange 4 along both side edges throughout the length of the plate, with the exception of the part where the integral extension 5 is carried. The parts of this turned-in flange or crimp 70 which are at the ends of the inclined portion 75 are flattened down upon the outer face of said inclined portion, so as to give strength and rigidity thereto. These bent-over ends lie in contact with the outer face of the inclined portion and greatly facilitate the cleaning of the corners of the pans, pots, or the like. The outer edge of the inclined portion 7 may be used for a scraper for pans and the like, as will be readily apparent. The knife- 80 edge 9 forms the paring implement, the implement being placed upon the vegetable and drawn toward the user, the paring passing through the slot 8. The slicer 5 is used in the same manner—namely, by engaging same 85 in the vegetable and drawing the implement toward the user. By projecting the two arms of the handle inwardly toward each other, then outwardly, as shown at 1', near the inner end of the plate 3, a convenient grip is formed 90 for the hand, allowing the operator to firmly grasp the handle and preventing slipping of the implement in the hand.

I desire to call particular attention to the 95 extreme simplicity of construction and the cheapness of the implement constructed as set forth. But two pieces of material are employed—a single piece of wire for the handle and frame and a single piece of sheet metal

to form the parer and slicer. The sheet-metal plate being secured firmly upon the arms of the wire frame and being of but one piece, all danger of the loosening of separate parts 5 connected together is obviated. The making of the parer and slicer of one piece of metal permits the stamping of this portion of the implement at one operation, as will be readily apparent.

10 Having fully described my invention, what I claim as new, and desire to secure by Letters Patent, is—

15 A paring and slicing implement which comprises a handle and frame formed of a single piece of wire doubled upon itself, the ends of the two strands being extended in parallel relation to one another, a slicer comprising an integral sheet-metal plate having an elongated slot formed therein extending in proximity to 20 the sides of said plate, an integral curved ex-

tension having a knife-edge on its lower face carried by one side of said slicer, the said ends of the frame engaging the outer face of said slicer and extending to a point below said slot, the sides of said plate being bent over to engage said frame except at the point of the curved extension, the part above said slot being bent at an angle and having its sides doubled upon themselves from a point at the ends of said frame, the upper end, of said inclined part being straight, the walls of said slot being bent in opposite directions, and a knife-edge on one of said walls, substantially as described.

25 In testimony whereof I affix my signature 30 in the presence of two witnesses.

GEORGE W. PAUL.
